UNITED STATES PATENT OFFICE.

JAMES E. ALLONBY, OF STAMFORD, CONNECTICUT.

EMERGENCY DEVICE FOR AUTOMOBILE-SPRINGS.

1,217,894.

Specification of Letters Patent.

Patented Mar. 6, 1917.

Application filed May 12, 1916. Serial No. 96,995.

To all whom it may concern:

Be it known that I, JAMES E. ALLONBY, a citizen of the United States, and a resident of Stamford, in the county of Fairfield and 5 State of Connecticut, have invented certain new and useful Improvements in Emergency Devices for Automobile-Springs, of which the following is a specification.

My invention relates to the construction 10 of temporary repairs for laminated vehicle springs.

The object of the invention is to provide a simple and inexpensive device adapted for ready application to a laminated vehicle 15 spring in cases where a break occurs in one or more of the laminations, for the purpose of providing a temporary repair.

The invention is especially useful for repairing springs of automobiles.

20 The invention consists, briefly stated, of a plate or truss adapted for application to the spring in a manner to span the break longitudinally and provided at its opposite ends with depending ears or lugs adapted to embrace the edges of the spring, one of the ears at each end being provided with a clamping set screw tapped into the ear and adapted to engage one edge of the spring while the ear on the other side engages the opposite 25 edge and is adapted to hold the broken or fractured leaves against longitudinal displacement.

The invention further consists of the construction of device and of its details as hereinafter more particularly described and then 30 specified in the claims.

Figure 1 of the accompanying drawings is a plan of a device embodying my invention.

Fig. 2 shows the same in edge view at one 40 end and in longitudinal central section at the other end.

Fig. 3 is an end view of the device.

1 indicates the body of the device consisting of a plate or other shape of steel or other 45 good material and formed preferably in a truss shape as indicated in side view. At each of its opposite ends the body 1 is provided with depending lugs or ears 2, 2'. The plate or body is adapted for application to the top of a broken or fractured laminated spring in a manner to bridge the broken or fractured spot while the lugs 2, 2' are adapted to engage the edges of the spring and to embrace the spring between them. The lugs 50 2 at one side are each provided with set screws 3 operable to clamp the device to the

spring in coöperation with the lugs or flanges 2' at the opposite side or edge of the spring in obvious manner. Preferably the lugs 2' are formed on their engaging surface 60 in such manner as to positively prevent the shifting of the broken plate of the spring longitudinally by biting into the edge thereof and for this purpose each may be provided with serrations extending transversely 65 across the edge of the spring as indicated in the side view Fig. 2.

In place of scorings or serrations such as shown, the surface might obviously be formed in other ways to positively hold the 70 two halves of the broken plate against longitudinal displacement with relation to the sound or unfractured plates from which the spring is built up.

As will be seen, my device can be readily 75 used with springs of different width by making the stem of the set screw 3 of sufficient length. In use the set screws are turned back sufficiently to permit the plate or truss 1 to be applied to the top of the spring with the 80 center portion of the truss or plate over the point of fracture and with the lugs extending down transversely to the spring along its edges. The set screws 3 are then turned up, thus binding the spring between the lugs 85 and causing the serrations or scorings or other irregular formation on the engaging face of the lugs 2' to bite all the leaves of the spring including the fractured leaf. This completes the repair. Ordinarily the use of 90 the screws 3 will be sufficient to firmly fasten the repair and prevent disengagement thereof during travel of the vehicle but, if desired, additional means may be employed for holding the repair against detachment, such 95 for instance as the yoke 4 applied to the top of the repair and fastened in place by the nuts 5.

What I claim as my invention is:

1. A repair for laminated vehicle springs 100 comprising a body adapted to span a break longitudinally of the spring and provided with two pairs of depending lugs or ears, one pair at each end, one of the ears of each pair being provided with a set screw adapted 105 to engage one edge of the spring while the opposite ear of said pair has an engaging surface bearing against the opposite edge.

2. A repair for laminated vehicle springs 110 consisting of a plate having at each end a pair of depending lugs and adapted to embrace the edges of the spring, one of said

lugs at each end carrying a set screw while the other is provided with a biting face engaging the edge of the laminations.

3. A repair for laminated vehicle springs comprising a body adapted for application to the top of the spring to span a break therein and having at each end a pair of depending lugs adapted to embrace the edges of the spring, one of said lugs being provided with a clamping set screw and the

other being provided with serrations upon its engaging face and extending transversely of the leaves of the spring.

Signed at Stamford in the county of Fairfield and State of Conn. this 26th day of 15 Feby. A. D. 1916.

JAMES E. ALLONBY.
